CLAIM

The ornamental design for a beverage container, as shown and described.

DESCRIPTION

FIG. 1 is a top perspective view the beverage container of the present design;

FIG. 2 is a bottom perspective view of the beverage container of FIG. 1;

FIG. 3 is a front view of the beverage container of FIG. 1;
FIG. 4 is a back view of the beverage container of FIG. 1;
FIG. 5 is a left-side view of the beverager container of FIG. 1;

FIG. 6 is a right-side view of the beverage container of FIG. 1;

FIG. 7 is a top view of the beverage container of FIG. 1; and,
FIG. 8 is a bottom view of the beverage container of FIG. 1.
The broken lines shown are included for the purpose of illustrating portions of the beverage container that form no part of the claim.

The beverage container is shown with symbolic breaks in its height in all drawing views. It is understood that patentability is based only on those portions of the article that are shown in solid lines, and the appearance of any portion of the article between the break lines forms no part of the claimed design.

1 Claim, 7 Drawing Sheets
